(57) **CLAIM**

The ornamental design for a strain relief cable, as shown and described.

DESCRIPTION

FIG. 1 is a front perspective view showing our new design for a strain relief cable,

FIG. 2 is a front view thereof,

FIG. 3 is a rear view thereof,

FIG. 4 is a left side view thereof,

FIG. 5 is a right side view thereof,

FIG. 6 is a top view thereof,

FIG. 7 is a bottom view thereof,

FIG. 8 is a front perspective view of a portion of the strain relief cable,

FIG. 9 is a front view thereof,

FIG. 10 is a rear view thereof,

FIG. 11 is a left side view thereof,

FIG. 12 is a right side view thereof,

FIG. 13 is a top view thereof; and,

FIG. 14 is a bottom view thereof.

The broken lines in the drawings depict portions of the strain relief cable that form no part of the claimed design.

1 Claim, 8 Drawing Sheets
